CLAIM

The ornamental design for a liquid dispenser, as shown and described.

DESCRIPTION

FIG. 1 is a perspective view of a liquid dispenser according to a first embodiment.

FIG. 2 is a front view thereof, the back view being identical.

FIG. 3 is a side view thereof.

FIG. 4 is a top view thereof.

FIG. 5 is a bottom view thereof.

FIG. 6 is a second perspective view thereof shown in an environmental state.

FIG. 7 is an exploded perspective view thereof shown in an environmental state.

FIG. 8 is a perspective view of a liquid dispenser shown in an environmental state according to a second embodiment; and, FIG. 9 is an exploded perspective view thereof shown in an environmental state.

Broken lines shown represent unclaimed subject matter and form no part of the claimed design.
